UNITED STATES PATENT OFFICE.

WALTER PINELL, OF BERLIN, GERMANY, ASSIGNOR TO SIEMENS & HALSKE AKTIEN-
GESELLSCHAFT, OF SIEMENSSTADT BEI BERLIN, GERMANY.

AUTOMATIC TELEPHONE SYSTEM.

Application filed August 19, 1926, Serial No. 130,127, and in Germany August 29, 1925.

The present invention relates to a circuit arrangement for automatic telephone systems, in which the selection of an idle line, which is to be used for the connection to be set up, is effected by in succession starting up several switches, which are connected in parallel to an incoming junction line, for the purpose of selecting an idle line. A system of this type is disclosed in the British Patent #241,287, issued Jan. 7, 1925, to J. E. Ostline and W. O. Passmore.

Now the present invention relates to a further development of the arrangement according to the British patent, and it especially relates to switches having several differently numbered groups of contacts. Over each of these differently numbered contact groups can be reached lines belonging to a particular traffic direction. Now the object 20 of the invention is to enable a free line to be selected in the particular traffic direction determined by the positioning of the group selecting switch, even when the number of lines in the selected group is greater than 25 the number of contacts for that group at the selecting switch. This is achieved by switching means, which function when all 30 the lines accessible over this particular contact group are engaged, and the said means start up a hunting switch, which is likewise connected to the incoming junction line and has connected to it other lines outgoing in the desired traffic direction.

In the Figures 1-3 are shown several examples of the invention, the circuit arrangements of which will now be described in detail.

The Figure 1 shows an example, in which connections to one traffic direction are set up over the fourth contact group of a group selector I.GW1 and the number of lines outgoing in this traffic direction is greater than the number of contacts in the fourth contact group at the selector I.GW1.

The test lead of each junction line contains a resistance R, the purpose of this will be explained hereafter. An end bank contact is directly earthed, and when the wiper of I.GW1 reaches this bank contact, a switching over is to take place to a second hunting switch connected in parallel with I.GW1 to the incoming junction line. The windings of the switch shaft operating magnets of the switches are shown in heavy black lines in order to distinguish the same

from the relays in the switches. When the incoming junction line is taken into use, the relay A1 is operated over its loop, furthermore the relays T1 and C1 are energized over: earth, T1, c-lead, contact 1m1, winding of the slow acting relay C1, off normal contact 2k1, battery, earth, and parallel to winding of C1 over a resistance winding of the relay C1, battery, earth. The energizing of the winding C1 causes the relay C1 to operate and it closes the following circuit: earth, contact 3c1, relay winding C2, relay V2, relay V1, battery, earth. The impulses received by the relay A1 cause it to alternately operate its contact 4c1 in known manner. The relay V1 closes a circuit for the lifting magnet H1 over earth, contact 5v1, back contact 6a1, magnet h1, back contact 7w1, battery, earth. The contact 6 gives the lifting magnet H1 the impulses for lifting in known manner controlled by the number dial. The selector is rotated over the desired contact group in known manner over earth, contact 8v1, back contact 9v2, rotary magnet D1, back contact 10p1, off normal contact 11k1, interrupter U1, battery, earth. When the selector finds an idle line the test relay P1 operates and opens the circuit of the rotary magnet. The test relay P1 is energized over earth, resistance R, segment and wiper of I.GW1, contact 23v1, winding P1II, winding P1I, relay HR1, battery, earth. The contact 24p1 in known manner short circuits the winding of P1. The resistance R is given such a magnitude that the relay HR1 cannot be operated even when the winding P1I is short circuited.

Should, however, the selector fail to find an idle outgoing line during the hunting movement over the contact group, it will finally reach the end back contact, which is directly connected to earth, as above mentioned. The relay HR1 can now be operated over the above mentioned circuit and at its contacts 19hr1 and 20hr1, it switches the incoming junction line over to the hunting switch FW1 located in parallel therewith. The relay HR1 at its contact 14hr1 closes an energizing circuit for the rotary magnet D2 of the switch FW1 as follows: earth, contact 14hr1, off normal contact 15k2, rotary magnet D2, back contact 16p2, battery, earth. When the switch FW1 is started up, the rotary magnet D2 is switched

over to the self interrupter U2 over the off normal contact 15k2. The switch FW1 is now tested by the test relay P2 in the same manner as that described above, and it arrests the switch on the first disengaged junction line in the outgoing traffic direction by opening the contact 16p2. The incoming junction line is now switched through to this line at the contacts 25p2 and 26p2. At the end of the conversation, both switches are released in known manner.

It should be noted that the contact groups of I.GW1, with which no hunting switches are associated in parallel, have the end bank contact earthed over the resistance R, which prevents the operation of the relay HR1. Known devices give the subscriber a busy signal.

The Figure 2 contains a circuit similar to that in the Figure 1. But here only a single test relay P3 is provided for both switches, furthermore, the circuit is so arranged that the selector switch cannot hunt when all the outgoing lines are engaged, and the incoming junction line is directly switched over to the hunting switch FW2 connected to in parallel with the switch I.GW2. The selector I.GW2 is started up on the origination of a call in the same manner as that described above. Each outgoing junction line is provided with a relay E1, E2, etc., the contacts 55e1, 56e2, etc. of which close a circuit for energizing the busy relay BR. When all the outgoing junction lines IV I.GW2 are engaged, the relay BR is energized and then prepares the circuit for the winding I of the relay HR2. The circuit for this winding is closed by a multiple contact 52mkIV as soon as the switch has reached the wanted contact group, for example the fourth group. If all the lines of this contact group be engaged, the closing of the contact 54br completes the circuit of the winding HR2I, and the switching over to the hunting switch FW2 is effected at the contacts 46hr2. At the same time the contact 41hr2 closes a circuit for the release magnet M2, which causes the I.GW2 to release immediately. The auxiliary relay HR2 finds a locking circuit over earth, contact 49v5, contact 50hr2, winding HR2II, battery, earth. The relay HR2 is made slow acting, so that the magnet H2 cannot operate wrongly when the relay V5 works irregularly. Here likewise the hunting switch is released in known manner at the end of the conversation.

Figure 3 shows the arrangement of two switches FW3 and FW4, which are parallel to different contact groups of the selector I.GW3. It is meant to represent the possibility of connecting up a large number of groups of lines going in different directions from a group selector. The line group contacts for each group of lines going in a

particular direction are represented by I and II. This circuit arrangement also requires only a single test relay P4. The method of operating will now be described. The selector I.GW3 is taken into use in the manner already described above. If a subscriber wishes to set up a connection in the traffic direction reached over the contact group I, and the I.GW3 has found all lines engaged, the relay HR3 is brought into action by the contact 74w3I which is an end bank contact of the first contact group. On reaching the first contact group, the contact 77mkI was closed, hence the rotary magnet D5 of the hunting switch FW3 is now closed over earth, contact 76hr3, contact 77mk1, off normal contact 78k5, rotary magnet D5, contact 81p4, battery, earth. When an idle junction line is reached, the switch is arrested by the opening of the contact 81p4. At the same time the incoming junction line is switched through to this idle line owing to the closure of the contacts 82p4 and 83p4. The operation of the relay HR3 caused the contacts 84hr3 and 85hr3 to be switched over to the switches FW3 and FW4, which are located in parallel. On energizing, the relay HR3 moves its contact 62hr3 into its operated position, this opens the circuit of the lifting and rotary magnets of I.GW3 and closes the circuit of the release magnet M3, thereby returning the I.GW3 to its normal position.

If the subscriber now wishes to make a call in the traffic direction reached over the second contact row of I.GW3, and if all the lines in this contact group be engaged, the switching over to the hunting switch FW4 takes place, because when the contact 75w3II is reached, the multiple contact 79mkII is closed, while the contact 72mkI remains open. Hence the rotary magnet D6 of the hunting switch FW4 is energized and it actuates this switch in the same manner as above described. At the end of the conversation, the connection is released in known manner.

What is claimed is:

1. In a telephone system, a main and a branch exchange, a group of lines connecting said main and branch exchanges, a numerical selector having access to said group for extending calls from the main to the branch exchange, a second group of lines connecting said main and branch exchanges, a hunting switch having access to said second group and connected in parallel with said selector, and means for operating said hunting switch to hunt for an idle line in the second group when all the lines in the first group are busy.

2. In a telephone system, a main and a branch exchange, a group of lines connecting said main and branch exchanges, a numerical selector having access to said group

for extending calls from the main to the branch exchange, a second group of lines connecting said main and branch exchanges, a hunting switch having access to said second group and connected in parallel with said selector, means for operating said hunting switch when all the lines in the first group are busy, a test relay in said selector, and means whereby said test relay tests the lines accessible to both said selector and said hunting switch.

3. In a telephone system, a main and a branch exchange, a group of lines connecting said main and branch exchanges, a selector having access to said group, means for operating said selector to select said group, means for operating said selector to hunt for an idle line in said group, a second group of lines connecting said main and branch exchanges, a hunting switch associated with said selector and having access to said second group, means for operating said hunting switch when all the lines in said first group are busy, and means responsive to said selector selecting said first group when all the lines therein are busy for automatically releasing said selector.

4. In a telephone system, a main and a branch exchange, a group of lines connecting said main and branch exchanges, a selector having access to said group, means for operating said selector to select said group, means for operating said selector to hunt for an idle line in said group, a second group of lines connecting said main and branch exchanges, a hunting switch associated with said selector and having access to said second group, means for operating said hunting switch when all the lines in said first group are busy, and means responsive to said selector selecting said first group when all said lines therein are busy for preventing the hunting operation of said selector.

5. In a telephone system, a main and a branch exchange, a group of lines connecting said main and branch exchanges, a selector having access to said group, means for operating said selector to select said group, means for operating said selector to hunt for an idle line in said group, a second group of lines connecting said main and branch exchanges, a hunting switch associated with said selector and having access to said second group, means for operating said hunting switch when all the lines in said first group are busy, and means responsive to said selector selecting said first group when all said lines therein are busy for automatically releasing said selector and for preventing the hunting operation of said selector.

6. In a telephone system, a main and a branch exchange, a group of lines connecting said main and branch exchanges, a selector having access to said group, means for operating said selector to select said group,

means for operating said selector to hunt for an idle line in said group, a second group of lines connecting said main and branch exchanges, a hunting switch having access to said second group, a chain relay associated with the test terminal of each of the lines in said first group, means for energizing said relays when their associated lines are busy, a group busy relay, contacts on said chain relays for closing an energizing for 70 said busy relay, a switching relay in said selector, contacts on said busy relay for preparing an energizing circuit for said switching relay, a switching device in said selector operated responsive to the operation of said selector to said group for completing the circuit for said switching relay, and contacts on said switching relay for switching over the incoming leads of said selector to said hunting switch and for causing the operation of said hunting switch.

7. In a telephone system, a main and a branch exchange, a group of lines connecting said main and branch exchanges, a selector having access to said group, means for operating said selector to select said group, means for operating said selector to hunt for an idle line in said group, a second group of lines connecting said main and branch exchanges, a hunting switch having access to said second group, a chain relay associated with the test terminal of each of the lines in said first group, means for energizing said relays when their associated lines are busy, a group busy relay, contacts on said chain relays for closing an energizing for 90 said busy relay, a switching relay in said selector, contacts on said busy relay for preparing an energizing circuit for said switching relay, a switching device in said selector operated responsive to the operation of said selector to said group for completing the circuit for said switching relay, and contacts on said switching relay for switching over the incoming leads of said selector to said hunting switch for causing the operation of said hunting switch and for preventing the hunting operation of said selector.

8. In a telephone system, a main and a branch exchange, a group of lines connecting said main and branch exchanges, a selector having access to said group, means for operating said selector to select said group, means for operating said selector to hunt for an idle line in said group, a second group of lines connecting said main and branch exchanges, a hunting switch having access to said second group, a chain relay associated with the test terminal of each of the lines in said first group, means for energizing said relays when their associated lines are busy, a group busy relay, contacts on said chain relays for closing an energizing for 110 said busy relay, a switching relay in 115 selector operated responsive to the operation of said selector to said group for completing the circuit for said switching relay, and contacts on said switching relay for switching over the incoming leads of said selector to said hunting switch for causing the operation of said hunting switch and for preventing the hunting operation of said selector.

- said selector, contacts on said busy relay for preparing an energizing circuit for said switching relay, a switching device in said selector operated responsive to the operation of said selector to said group for completing the circuit for said switching relay, and contacts on said switching relay for switching over the incoming leads of said selector to said hunting switch, for causing the operation of said hunting switch, for preventing the hunting operation of said selector, and for closing a circuit for releasing said selector.
9. In a telephone system, a main and a branch exchange, a group of lines connecting said main and branch exchanges, a selector having access to said group, means for operating said selector to select said group, means for operating said selector to hunt for an idle line in said group, a second group of lines connecting said main and branch exchanges, a hunting switch having access to said second group, a switching relay in said selector, means for operating said relay responsive to the operation of said selector to said group when all the lines in the
- 10 15 20 25

first group are busy, and contacts on said relay for causing the operation of said hunting switch and for preventing the hunting operation of said selector.

10. In a telephone system, a main and a branch exchange, a group of lines connecting said main and branch exchanges, a selector having access to said group, means for operating said selector to select said group, means for operating said selector to hunt for an idle line in said group, a second group of lines connecting said main and branch exchanges, a hunting switch having access to said second group, a switching relay in said selector, means for operating said relay responsive to the operation of said selector to said first group when all the lines in the first group are busy, and contacts on said relay for causing the operation of said hunting switch, for preventing the hunting operation of said selector, and for closing a circuit to release said selector.

40 45
In witness whereof, I hereunto subscribe my name this 26th day of July, A. D. 1926.

WALTER PINELL.
